UNITED STATES PATENT OFFICE

168,910

AERIAL AMUSEMENT RIDE CAR OR SIMILAR ARTICLE

Earl L. Reedy, Sacramento, Calif.

Application November 24, 1951, Serial No. 17,513

Term of patent 14 years

(Cl. D34—15)

To all whom it may concern:

Be it known that I, Earl L. Reedy, citizen of the United States, residing at Sacramento, State of California, have invented a new, original, and ornamental Design for an Aerial Amusement Ride Car or Similar Article, of which the following is a specification, reference being had to the accompanying drawings, forming a part thereof.

Fig. 1 is a fragmentary side elevational view of an aerial amusement ride car or similar article, showing my new design;

Fig. 2 is a fragmentary top plan view thereof; and

Fig. 3 is a front elevational view thereof to a reduced scale.

Part of the front supporting post has been broken away in Figs. 1 and 2 for convenience of illustration.

I claim:

The ornamental design for an aerial amusement ride car or similar article, as shown and described.

EARL L. REEDY.
